DESIGN FOR A PEDATE VIBRATOR

Samuel B. Sklar, New York, N. Y.

Application December 23, 1938, Serial No. 81,957

Term of patent 7 years

To all whom it may concern:

Be it known that I, Samuel B. Sklar, a citizen of the United States, residing at New York, in the county of New York and State of New York, have invented a new, original, and ornamental Design for a Pedate Vibrator, of which the following is a specification, reference being made to the accompanying drawing, forming part thereof.

The figure is a perspective view of a pedate vibrator showing my new design.

The other side of the vibrator is substantially like the side shown.

I claim:

The ornamental design for a pedate vibrator, substantially as shown and described.

SAMUEL B. SKLAR.
